HANG-FIRE DEVICE FOR BREECH-LOADING ORDNANCE.

1,302,530.

Specification of Letters Patent.

Patented May 6, 1919.

Application filed November 24, 1915. Serial No. 63,286.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Hang-Fire Devices for Breech-Loading Ordnance, 10 of which the following is a specification.

This invention relates to the type of hang fire device that comprises a safety catch or bolt which is carried by the gun itself and is under the control of a relatively stationary member, this catch being adapted to engage with the breech actuating hand lever or other suitable part of the breech actuating mechanism for the purpose of preventing the latter from being operated to open the breech 20 until after a discharge has occurred and the gun is regaining its firing position during which time the stationary member displaces the catch into a position to enable the hand lever to be operated to open the breech.

According to this invention the safety catch or bolt carried by the gun is under the control of a device so constructed and arranged in relation to the relatively stationary member that it will be automatically operated to displace the catch or bolt axially and disengage it from the breech actuating mechanism as the gun returns to its run-out position after recoil and to hold the catch or bolt in this position when the device 35 moves clear of the said stationary member toward the end of the run out movement of the gun. The said catch or bolt may be controlled by a spring and the disengaging device may be in the form of a cam which is

40 pivotally connected to the said catch or bolt and bears against a contiguous part of the breech end of the gun. The said cam is adapted to be moved about its pivot by the stationary member (without disengaging 45 the catch or bolt) during the recoil of the gun so as to assume such a position that on the run out of the gun, it will be moved in the reverse direction by the said member, to bring a part thereof against the contiguous 50 part of the breech end of the gun and to thereby disengage the catch to enable the breech to be opened.

In order that the said invention may be clearly understood, and readily carried into

effect, we will describe the same more fully 55 with reference to the accompanying drawings, in which:

Figure 1 is a side elevation showing in a more or less diagrammatic manner the breech end of a gun provided with our improvements, this figure also showing the aforesaid stationary member with which the disengaging device is adapted to coöperate; in this figure the tripping cam is shown in the position it occupies when the breech is 65 closed and the gun is in its run out position.

Fig. 2 is a rear elevation of the upper part of Fig. 1 with a portion in section on the line 1, 1 of Fig. 1. 70

Figs. 3, 4 and 5 are views similar to Fig. 1 showing the position of the parts during the recoil movement, the run out movement and the final part of the run out movement of the gun respectively. 75

Fig. 6 is a local section taken approximately on the line 2, 2 of Fig. 5, and

Figs. 7 and 8 are views similar to Figs. 5 and 6 showing the position of the parts during the initial opening movement of the 80 breech block.

In all these figures, A is the breech end of the gun and B is the breech actuating hand lever. C represents the aforesaid spring controlled catch or bolt and D represents the 85 cam constituting the disengaging device of the said catch or bolt; this cam is hereinafter referred to as the tripping cam. E represents the aforesaid stationary member for operating the cam D. 90

In the example shown the catch or bolt C is in the form of a spring controlled plunger arranged vertically in the breech end of the gun and formed at its upper end with a beveled surface *c* which engages with a corresponding surface *b* (Fig. 2) on the breech actuating lever B during the closing movement of the latter so as to displace the plunger and enable it to engage with a pocket or recess *B'* (Fig. 2) in the hand lever. At its lower end the plunger C has an enlargement *C'* to which the aforesaid tripping cam D is pivoted at *d*, this cam bearing against the under surface of the breech end of the gun. The tripping cam has a toe-piece *d'* which engages with the stationary member E during the recoil of the gun and causes the tripping cam D to be angularly 95 100 105

displaced as shown by Fig. 3. This displacement of the cam causes a projection d^2 thereon to engage with the under side of the breech end of the gun and to thereby partly 5 withdraw the plunger C and also allow the stationary member to clear the toe-piece d' whereupon the cam is moved by the spring of the plunger C until a flat surface d^3 on the said cam bears against the under side of the 10 breech end of the gun as shown in Fig. 4; the toe-piece d' on the cam is then in a position to be acted upon by the stationary member E as the gun performs its run out movement (Fig. 4). The tripping cam is retained 15 in this position by the spring of the plunger C until during the run out movement the toe-piece reengages with the stationary member (Fig. 4) and moves the cam, as shown by Fig. 5, in the reverse direction to that in 20 which it was moved by the member during recoil, whereby arms or projections d^4 on the cam are caused to engage in notches b' formed in the under surface of the breech end of the gun; the cam is thus retained in 25 this position with the plunger disengaged from the pocket or recess B' in the breech actuating hand lever. The tripping cam is provided with an operating arm D' which is acted upon by an inclined surface D² on 30 the breech block D³ when the latter is moving in the direction of the arrows in Figs. 6 and 8 to its open position, to move the tripping arm D in an anti-clockwise direction and disengage its arms or projections d^4 35 from their notches b' (see Fig. 7), whereupon the spring of the plunger C causes the latter to rise and return the cam to its original position shown by Fig. 1. The operating arm D' serves as a finger piece by means of 40 which the cam D can be displaced to disengage the plunger C from the breech actuating hand lever B when required, and is disposed in a recess cut in the side of the breech end of the gun.

45 When the invention is as in the example shown applied to ordnance of the semi-automatic and quick firing type, the aforesaid stationary member E may take the form of a projection on the operating pawl E^x, its 50 position being such that when the pawl is in the condition for the semi-automatic working of the gun, this projection will occupy the position shown by broken lines in Fig. 3 and will thus lie out of the path of recoil of 55 the toe-piece d' of the tripping cam D.

What we claim and desire to secure by Letters Patent of the United States is:—

1. In a hang fire arrangement for ordnance the combination with the breech actuating hand lever, the hang fire catch carried by the gun and adapted to engage with the hand lever, and the relatively stationary member for displacing said catch during the run out movement of the gun after recoil, of 60 a device operating upon said catch and oper- 65

ated by the relatively stationary member to disengage the catch during the run out movement of the gun and to hold it in this position when the device moves clear of the said member toward the end of the run out movement. 70

2. In a hang fire arrangement for ordnance the combination with the breech actuating hand lever, the hang fire catch carried by the gun and adapted to engage with the hand lever, and the relatively stationary member for displacing said catch during the run out movement of the gun after recoil of a device bearing against a contiguous portion of the gun and being operated by the relatively stationary member to disengage the catch during the run out movement of the gun and to hold it in this position when the device moves clear of the said member toward the end of the run out movement. 80 85

3. In a hang fire arrangement for ordnance, the combination with the breech actuating hand lever, the hang fire catch carried by the gun and adapted to engage with the hand lever, and the relatively stationary member for displacing said catch during the run out movement of the gun after recoil, of a device operating upon said catch and operated by the relatively stationary member to disengage the catch during the run out movement of the gun and to hold it in this position when the device moves clear of the said member toward the end of the run out movement. 90 95

4. In a hang fire arrangement for ordnance, the combination with the breech actuating hand lever, the hang fire catch carried by the gun and adapted to engage with the hand lever, and the relatively stationary member for displacing said catch during the run out movement of the gun after recoil, 100 of a device carried by said catch and operated by the relatively stationary member to disengage the catch during the run out movement of the gun and to hold it in this position when the device moves clear of the said member toward the end of the run out movement. 105 110

5. In a hang fire device for ordnance, the combination with the breech actuating hand lever, the hand fire catch carried by the gun 115 and adapted to engage with the hand lever, and the relatively stationary member for displacing said catch during the run out movement of the gun after recoil, of a device bearing against a contiguous portion of the gun and carried by said catch, this device being operated by the relatively stationary member to disengage the catch during the run out movement of the gun and to hold it in this position when the device 120 125 130

moves clear of the said member toward the end of the run out movement.

6. In a hang fire device for ordnance, the combination with the breech actuating hand lever, the hang fire catch carried by the gun and adapted to engage with the hand lever, and the relatively stationary member for displacing said catch during the run out movement of the gun after recoil, of a device bearing against a contiguous portion of the gun and carried by said catch, this device being operated by the relatively stationary member to disengage the catch during the run out movement of the gun and to hold it in this position when the device moves clear of the said member toward the end of the run out movement, and means for displacing said device, during the opening of the breech, to enable the catch to assume a position to reengage with the hand lever when the breech is closed.

7. In a hang fire device for ordnance, the combination with the breech actuating hand lever, the hang fire catch carried by the gun and adapted to engage with the hand lever, and the relatively stationary member for displacing said catch during the run out movement of the gun after recoil, of a cam device bearing against a contiguous portion of the gun and being operated by the relatively stationary member to displace the catch longitudinally out of engagement with the hand lever during the run out movement of the gun and to bring a part of said cam device into engagement with part of the gun to hold the device in this position when it moves clear of the said member toward the end of the run out movement, said cam device having an arm adapted to be operated upon by an inclined surface on the breech block, during the opening movement of the latter, to liberate said device and permit the catch to assume a position to reengage with the hand lever when the breech is closed.

hold the device in this position when it moves clear of the said member toward the end of the run out movement.

8. In a hang fire device for ordnance, the combination with the breech actuating hand lever, the spring controlled hang fire catch carried by the gun and adapted to engage with the hand lever, and the relatively stationary member for displacing said catch during the run out movement of the gun after recoil, of a cam device bearing against a contiguous portion of the gun and being operated by the relatively stationary member to displace the catch longitudinally out of engagement with the hand lever during the run out movement of the gun and to bring a part of said cam device into engagement with part of the gun to hold the device in this position when it moves clear of the said member toward the end of the run out movement, said cam device having an arm adapted to be operated upon by an inclined surface on the breech block, during the opening movement of the latter, to liberate said device and permit the catch to assume a position to reengage with the hand lever when the breech is closed.

In testimony whereof we affix our signatures in the presence of two witnesses.

ARTHUR TREVOR DAWSON.
GEORGE THOMAS BUCKHAM.
